UNITED STATES PATENT OFFICE.

FRITZ KUCHENMEISTER, OF HENNEF, GERMANY, ASSIGNOR TO GEBRÜDER STEIMEL,
OF HENNEF, GERMANY.

DAIRY MACHINE.

Application filed February 19, 1926, Serial No. 89,456, and in Germany February 28, 1925.

Many forms of small dairy outfits are already known, but without exception they are set up of four separate machine, namely: the centrifuge, churn, butter kneader and 5 motor. In these known arrangements an important part is played by the driving means, that is belt transmission or similar reducing or change speed intermediate drives, which are expensive to provide. Besides 10 this the space occupied by such means is very great and they can seldom be set up in rural households. All too seldom indeed is a milk room provided. The present small dairy outfit can be set up in a space 15 of a square metre.

This invention relates to a combination of motor, centrifuge, churn and butter kneader, in such a manner, that all the individual machines are mounted on or in a single machine 20 pedestal and thus form only a single apparatus. By means of a clutch device any desired individual machine can be set in action. In order to keep the power consumption low and to use a weak electric 25 motor, it is arranged that during churning and kneading, the rapidly rotating separator drum acts as regulating and evening flywheel: that is the unavoidable jerking variations in power requirement are evened out 30 by the momentum of the rapidly rotating flywheel. The accompanying drawings illustrate two embodiments of a small dairy machine in accordance with the invention.

Figure 1 shows an outfit with a suspended 35 separator drum.

In Figure 1 *a* is the pedestal of the machine which carries a kneading plate *b*. Beneath this stands a churn *c*. To the right above is a drive housing *d*. On this is 40 screwed a motor *e*. The armature shaft *f* of the motor is of worm form opposite a worm wheel *g* and meshes therewith. In this way a shaft *h* is driven. In addition a toothed wheel *i* is mounted on the armature shaft and meshes with a pinion *k*. This carries a 45 drive spindle *l* which rotates a separator drum *m* through a coupling. *n* is a collecting cover which leads off separately the

cream and skimmed milk. The whole milk to be skimmed is poured into a bowl *o* and is 50 led into the drum *m* through a pipe *p*.

The shaft *h* carries a toothed wheel *q* which meshes with teeth *r* in the kneading table *b* and thus drives it. There is also a bevel wheel *s* on the shaft *h*, which meshes 55 with a bevel wheel *t* and thus drives the spindle *u* provided with a coupling for the shaft *v* of the churn beater 4 which is thus rotated.

A spindle *x* is borne in a vertical arm *w* of the pedestal *a*, on which spindle rotates a kneading roller 2. This is driven by a toothed wheel *z* meshing with a toothed crown *y* on the kneading plate *b*.

The individual machines are put in and 60 out of gear by longitudinally sliding the shaft *h* by a screw *j* engaging in a thread 3 in the drive housing *d*.

Figure 1 shows the machine with the 65 churn in gear. The separator drum runs during churning and kneading. If the churn is to be put out of gear the screw *j* is so turned that the shaft *h* moves to the right. The wheel pair *s*—*t* goes out of mesh and the machine is now ready for separating, 70 while the churn and kneader remain stationary. By further turning the screw *j* the shaft *h* moves still further to the right, so that the wheel *q* meshes with the teeth *r* and the kneading plate is rotated. At the same 75 time the roller 2 is also driven through the crown *y* and wheel *z*.

A hand crank can be secured to the shaft 80 *h* in front of the screw *j* for use in case of interruption in the supply of electric power.

In Figure 2 the same arrangement is shown with a standing instead of suspended separator drum. The action is the same as that above described.

What I claim as my invention is:

1. In a small dairy outfit embodying a pedestal, a kneading plate and a churn carried thereby, a motor, and a connection between the motor and the kneading plate and the churn, the combination with such elements of a separator drum arranged to run 90

95

95

during churning and kneading and to serve as a regulating fly wheel to balance the churn and the kneader.

2. In a dairy machine, a butter churn, and
5 its shaft, a butter kneader, a motor and its
shaft, a horizontal shaft with gearing be-
tween the motor shaft and the horizontal
shaft, operative connections between the
horizontal shaft and the shaft of the butter

kneader and the churn, shiftable connections 10
between the butter kneader and the churn,
said connections embodying a worm wheel
having teeth sufficiently long to permit of
the shifting of the horizontal shaft to drive
the desired element irrespective of the other. 15

In testimony whereof I affix my signature.

FRITZ KUCHENMEISTER.
